UNITED STATES PATENT OFFICE.

FRED I. JADEN, OF HASTINGS, NEBRASKA.

OIL CAN.

Application filed April 4, 1928. Serial No. 267,326.

My invention relates to an oil can and embodies in some of its phases certain features designed to constitute an improvement on the oil can forming the subject matter 5 of an application filed by me November 19th, 1927, Serial No. 234,401, the said oil can of the present invention embodying also new and novel features designed to promote efficiency in the oil can, the whole assemblage 10 being designed to carry further in the direction of perfection an oil can of the general character forming the subject matter of my prior application referred to.

The nature of my invention and its distinguishing features and advantages will more clearly appear as the description proceeds.

Reference is to be had to the accompanying drawing forming part of this specification, it being understood that the drawings 20 are merely illustrative of one example of the invention.

Figure 1 is a vertical section of an oil can embodying my present invention;

Figure 2 is a horizontal section on the line 25 2-2 of Figure 1;

Figure 3 is an elevation of my oil can, the spout of the oil can being removed and the remaining elements entering into the oil can 30 being shown partly disassembled;

Figure 4 is an elevation of the oil can spout.

Referring to the parts of the invention represented in the illustrated example, a can body 10, usually cylindrical, and having a bottom 11, has secured to the bottom centrally thereof a plug 12, the reduced lower end of which plug is flanged over or upset as at 13 against the under side of the bottom 35 11 to securely hold said plug in place. A packing ring 111 of cork or equivalent packing material is disposed on the bottom 11, which bottom is cup-shaped to extend about the cylindrical body 10 at the lower end. 40 The packing ring 111 provides an arrangement forming a leak-proof joint between the cylindrical can body 10 and the bottom 11, and permits of making the parts of the pumping assemblage hereinafter referred to, 45 quickly accessible that the entire bottom 11 can be quickly removed from the body in a manner hereinafter referred to. The making of the cup-shaped bottom 11 removable 50 as referred to enables the oil can to be made 55 with less parts and at less cost.

An assemblage comprising the filling neck and its cap 14 in the present invention includes a filling neck 15 which has a threaded zone 16. Above the threaded zone 16 is a plain zone 17, the threaded zone 16 being 60 adapted to be engaged by the internal threaded zone 18 and a plain zone 19 on the cap conforms to the plain zone 17 on the neck. The zone 17 constitutes a guide for the cap 14 and holds the cap in line in placing the same on the neck so that the cap always starts straight on the threads 16 and makes it impossible to "cross-thread" the cap on the neck. This constitutes an important 65 improvement as it is often necessary to remove the cap to pour oil in the oiler when the weather is cold and when mittens or gloves are being worn by the user. Under these conditions it is very difficult to start the ordinary cap straight on the threads of 70 the filling neck, said threads in practice being formed both externally and internally, the present example showing the threads of the neck externally.

A packing ring 114 is employed in practice 80 in the cap 14 at the top seating on top of the neck 15.

The pumping assemblage of the present invention promotes simplicity of construction and involves the minimum number of 85 parts. The plug 12 has a polygonal surface 112 for convenience in holding with a wrench for assembling or disassembling the parts. Above the polygonal body 112 of plug 12 there rises a neck 20 having threads 120 90 which are engaged by corresponding threads on the lower end of a discharge tube 21 which extends from the said neck through the top of the can body. The upper end of the discharge tube 21 is threaded and receives a 95 nut 22, said nut having external threads 122 to receive a flanged nut or bonnet 23 the flange of which bonnet bears downwardly upon and serves to clamp against an annular shoulder 24 on the lower end of the nozzle 100 25 of the oil can to make the nozzle readily removable.

The neck 20 constitutes an oil chamber in which is a ball valve 26 controlling the flow of fluid into said oil chamber through the bottom inlet 27 thereof from the central chamber 28 of plug 12. The ball check valve 26 is under pressure of a spring 29, and in the neck 20 is fitted a stop 30 to be 105 hereinafter referred to.

Threaded into the plug 12 at opposite sides are tubes 31 and 32. At the outer end of the tube 31 is an oil inlet 33 controlled by a ball valve 34 or other check valve under the pressure of a coil spring 35 which abuts at one end against the stop 36 generally corresponding to stop 30 and to be hereinafter referred to.

Tapped into the tube 32 is the reduced end 38 of pump cylinder 37 in which operates a piston 39. A piston rod 40 connects with the piston 39 by a ball head 41 accommodated in a socket 42, as shown in my previous application. Also, as in my previous application, said piston rod 40 extends upwardly through the can body top 43. Within the can body the piston rod 40 passes through the tapered housing 44 which abuts at one end against the can body top 43 and extends at its lower end to the piston 39. On the rod 40 at the top 43 of the can is a felt washer 45 held tightly against the top of the cover 43 and disposed about the rod 40 to prevent leakage. Pressure is applied to the washer 45 by a spring 46 surrounding the projecting upper end of the plunger rod 40. An operating arm 47 is placed on the reduced upper end of rod 40 and held against displacement by a cap 30 nut 48.

The numeral 50 indicates a handle on the can body at a side thereof.

Reverting to the stops 30, 36, each is disposed at that end of the springs 29, 35 farthest from the balls 26, 34. The stops 30 or 36 are essentially the same and are formed of a short strip of metal having the bend or protuberances 31, 51 projecting toward the ball valves 26, 34. In addition to taking the thrust of the springs at the end adjacent the bends 31, 51, said bend or protuberances 31, 51 constitute stops limiting the movement of the valves toward said stops so that the springs 29, 35 are always maintained with the convolutions thereof open for the free flow of oil through the neck 20 and the tube 31.

It will be seen by a comparison of Figures 1 and 3 that a convenient mode of assembling or disassembling in the desired oil can may be practiced. Figure 3 shows that the bottom 11 has been detached from the lower end of the body 10 and as a unit with the bottom there is removed the element 12, the fittings 31, 32, the pump cylinder 37 and the discharge pipe 21 as well as the valves in the element 31 and the neck 20 of element 12. On the other hand there is removed with the detachable top 43 the piston 31, its rod 40, the housing 44, the spring 46 and the operating member 47 together with the neck 15 and cap 14. The nut 22 is turned off from the upper end of the discharge pipe 21 to permit said discharge pipe being removed with the bottom 11. If desired, also, the

bonnet 23 may be detachable from the nut 22 to permit removal of nozzle 25 as shown in Figure 4.

I would state furthermore that while the illustrated example constitutes a practical embodiment of my invention, I do not limit myself strictly to the exact details herein illustrated, since manifestly, the same can be considerably varied without departure from the spirit of the invention as defined in the appended claims.

I claim:

1. An oil can including a can body open at the top and bottom, a bottom detachably held to the bottom of said body, a fitting permanently secured to the bottom, means forming an oil chamber and having an inlet, said means attached to said fitting; a discharge tube held to said fitting to be removable with said fitting and the bottom, a pump cylinder supported on said fitting to receive oil therefrom and to be detachable with said fitting and with said means, said discharge tube and the bottom as a unit, a detachable top on the body, a piston operating in said cylinder, a piston rod connected with said piston and operatively associated with said top and removable and replaceable with the top, a capped filling neck held to the top to be removable therewith, a nozzle, and means detachably connecting said nozzle with the discharge tube, the nozzle and the means to connect the nozzle with the discharge tube being removable with the top.

2. An oil can including a can body open at the top and bottom, a bottom detachably held to the bottom of said body, a fitting permanently secured to the bottom, means forming an oil chamber and having an inlet, said means attached to said fitting, a discharge tube held to said fitting to be removable with said fitting and the bottom, a pump cylinder supported on said fitting to receive oil therefrom and to be detachable with said fitting and with said means, said discharge tube and the bottom as a unit; together with a nozzle, a top on the body to which said nozzle is held, and a piston and piston rod supported by the top, said piston adapted to operate in said pump cylinder.

3. An oil can, including a body, a pump cylinder within the body, means to supply oil to said pump cylinder, a piston operating in said cylinder, a piston rod rising from said piston and extending through the top of the can body, and a tubular housing surrounding the piston rod within the body and extending downwardly from said top to serve as a stop to limit the upward stroke of the piston.

4. In an oil can, a body having a bottom, an element having an oil chamber disposed near the bottom of the body, a tube forming an inlet to said oil chamber, a ball check valve in said tube, a spring pressing on said

ball check valve, and a strip in said tube at the inner end of the spring forming an abutment for the spring at that end, said strip having a bend toward the ball check valve 5 within the spring and constituting a stop for the ball check valve.

5. In an oil can, a body having a bottom, an element having an oil chamber disposed near the bottom of the body, a tube forming 10 an inlet to said oil chamber, a ball check valve in said tube, a spring pressing on said ball check valve, and a strip in said tube at the inner end of the spring forming an abutment for the spring at that end, said strip 15 having a bend toward the ball check valve

within the spring and constituting a stop for the ball check valve; together with a discharge tube communicating with the oil chamber, a check valve controlling the flow of oil from the oil chamber to said discharge 20 tube, a spring pressing on said valve, and a strip forming an abutment on the upper end of said spring, said strip having a bend therein within the spring and toward the valve. 25

Signed at Hastings in the county of Adams and State of Nebraska this 31st day of March, A. D. 1928.

FRED I. JADEN.
